Fredrick W. Knappmeier.

By Hugh N. Wagner,
Attorney.

UNITED STATES PATENT OFFICE.

FREDRICK WILLIAM KNAPPMEIER, OF PONDS, MISSOURI.

COIL BOX.

Original application filed March 24, 1923, Serial No. 627,252. Divided and this application filed October 5, 1923. Serial No. 666,717.

To all whom it may concern:

Be it known that I, FREDRICK WILLIAM KNAPPMEIER, a citizen of the United States, residing at Ponds, in the county of St. Louis 5 and State of Missouri, have invented certain new and useful Improvements in Coil Boxes, of which the following is a specification.

This invention relates to ignition systems and is a division of the matter shown in my 10 application #627,252, filed March 24, 1923 and relates especially to a box or container for induction coils.

The principal object of the invention is to provide an improved box or container from 15 which, by reason of the specific construction of the container, the induction coil may be removed with as little disturbance of the wires as possible.

With the above and other objects in view 20 as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

In the accompanying drawings forming 30 part of this specification, in which like numbers of reference denote like parts wherever they occur,

Figure 1 is a plan view of the coil box.

Figure 2 is a side view of the same, with 35 parts broken away to show a vertical central section.

Figure 3 is a front view of the coil box; and

Figure 4 is a bottom view of the same.

40 This box or container is indicated in general by the numeral 1 and the coil contained therein at 2, which may, as designed have a wooden casing 3. The box itself comprises a sheet metal structure having a back wall 5 45 from which project securing lugs 14 having screw openings 15 therein for the reception of screws for holding the box to the instrument board of an automobile. These lugs project from the lateral edges of the rear

wall and from the same rear wall project 50 forwardly the side walls 4, having their forward edges turned inwardly to form spaced flanges 9 so as to provide a wide slot 4^b between them. At 6 is shown a bottom which extends forwardly from the lower edge of 55 the back wall 5 and has side edges flush with the side walls, said bottom having a centrally disposed opening 7 to receive the bottom connection or binding post 8 of the coil. Rested on the bottom is an insulating plate 60 having an opening 12 through which the binding post 8 projects, the bottom 11 of the coil resting on this insulating plate. It will be noted that the lugs 14 are preferably extensions of bars 13 which are fixed to the 65 back wall. At 16 is a removable cover consisting of a top 17, side walls 18; a rear wall 19, and front wall 20, the latter having a thumb piece 21 to aid in its removal.

It will be seen that the coil has the usual 70 connections 22 and 23 which slide in the slot 4^b. With this construction it is easy to see that upon removal of the cover and disconnection of the bottom wire the coil with its connection to the binding posts 22 and 23 75 may be slid upwardly out of the container.

Having thus described the invention, what is claimed as new, is:

A container for ignition coils consisting of a sheet metal structure having a back wall 80 provided on its lateral edges with securing lugs, side walls extending forwardly from said lateral edges and having their forward edges turned inwardly toward each other to form spaced flanges and providing a slot between said flanges, a bottom extending forwardly from the lower edge of said back wall and having side edges flush with said side walls, said bottom having a centrally disposed opening to receive the bottom connection of an ignition coil, the slot accommodating the side connections of said coil, and a removable top fitting said back, sides and flanges at their upper edges.

In testimony whereof I heretunto affix my 95 signature.

FREDRICK WILLIAM KNAPPMEIER.
